UNITED STATES PATENT OFFICE.

JOSEPH A. SKOGLUND, OF ST. PAUL, MINNESOTA.

ARCH SUPPORT.

Application filed May 12, 1924. Serial No. 712,600.

My invention relates to improvements in arch supports.

An object of the invention is to provide an improved and relatively simple and inexpensive device of the present nature designed to be worn with comfort upon the foot and adapted to effectively reinforce the transverse and longitudinal arches thereof.

With the foregoing and other objects in view, which will appear in the following description, the invention resides in the novel combination and arrangement of parts and in the details of construction hereinafter described and claimed.

15 In the drawing, Fig. 1 is an elevational view of an arch support embodying my invention, the same being illustrated as worn within a shoe; Fig. 2 is a perspective view of the support showing the form thereof that 20 is naturally assumed in the absence of the application of any force thereto; Fig. 3 is also a perspective view of the support, but in this view the butt of the pad is shown as being flattened and the elastic band, between the 25 longitudinal margins of said pad, correspondingly stretched; Fig. 4 is a central, longitudinal sectional view of the support; Fig. 5 is a fragmentary, transverse sectional view taken as on the line 5—5 of Fig. 4; Figs. 30 6 and 7 are similar views, the former showing the pad arched transversely on a wearer's foot with the weight removed therefrom, the latter showing the position assumed by said pad under the weight of the wearer and Fig. 35 8 is a perspective view of the arch bracing pad, the top thereof being turned back to show the cushioning device inside of the pad.

Referring to the drawings, it will be seen that my improved support includes a foot 40 encircling band A and an arch bracing pad B associated therewith.

The band A, which is designed to fit over the instep and under the main arch of a foot 45 may comprise a strip of elastic material, such as surgical elastic, sewed together at its ends, but preferably consists of a non-elastic top or instep engaging portion a' of soft leather and a bottom portion a² of elastic, the same being seamed at its ends to the ends of the 50 instep engaging portion a' to complete the band. The top portion a' is peculiarly

formed in that the upper and lower edges are cut low, as shown, and in that said portion is perforated as at 10. By thus shaping said upper and lower edges of said portion a', 55 the same is brought well down on the top of the foot, where the slope thereof is less pronounced. This promotes comfort in the wearing of said band A and at the same time provides for the normal positioning of the ends 60 of the band portion a², as shown in Fig. 1, whereby the tension of the band at the bottom of the foot is applied substantially upward and well back in the main arch. In addition to lowering the area of contact on the 65 top of the foot, the non-elastic portion a' of the band avoids drawing of the foot and, being perforated, as explained, ventilates the foot throughout the engaged area of the instep.

70 The band A, though preferably associated with the pad B, serves in itself as a transverse arch support, the elasticity of the band operating to yieldingly prevent the lateral spreading of the foot, whereby said arch is 75 sustained.

The pad B includes elongated top and bottom pieces 11, 12 of leather or other flexible material, said pieces being joined at their margins by stitching or otherwise. Said pad B reaches forwardly of the band A, the shank b of the pad being secured transversely of the band A and at the bottom of the elastic portion a² thereof. The attachment of the pad B to the band A is made by sewing one to 80 the other. With the shank b of the pad B flat, the band portion a² is sewed to one side edge of said shank as by a seam 13 (Fig. 3), the other side edge of the shank b and band portion a² being united with a seam, as at 85 14, after the band portion a² has been stretched to that extent approximating the degree to which said portion is stretched, when the band A is applied to a foot. The rearward end of the shank b falling short 90 of the rearward edge of the band portion a² (Fig. 4), is sewed to said portion a² longitudinally thereof as by means of a seam 15. The band A and pad B being thus united 95 results in the constant tendency of the pad B to arch upward against the longitudinal arch 100 of the foot. This construction is otherwise

advantageous, since it permits of the use of maximum lengths of elastic in the band, whereby thickness of the stock may be held to the minimum in the promotion of comfort to the wearer, without sacrificing any essential part of the gripping action of said band upon the foot.

Encased within the forward end of the pad B, between the top and bottom pieces 11 and 12 thereof is a cushioning device c, (Fig. 8), which consists of a form retaining body 16 of stiff leather, pressed metal or other material formed with a convex upper surface. Traversing said body 16 and the forward end 15 of the pad B to which said body 16 is medially applied, is an arched spring leaf 17, the ends thereof projecting beyond the sides of the body 16 in wing-like fashion. Said ends of said leaf 17 conform with the contour of 20 the upper convex surface of the body 16. Being secured to said body and to the bottom piece 12 of the pad B by rivets 18 binding together all of said parts 16, 17 and 12, said leaf 17 and body 16 together supply a yielding 25 arch-like reinforcement for the forward end of the pad B.

With the band A in place on a wearer's foot, said band operates to prevent the spreading of the foot and thereby sustain the transverse arch, as above explained.

The pad B secured to said band A and actuated thereby to arch the same longitudinally at the shank thereof, yieldingly bears upwardly against the longitudinal arch of the 35 foot, thus acting to support said arch. Located beneath the metatarsal bones, the cushioning device c, within the forward end of the pad B, operates to yieldingly sustain the metatarsal arch.

From the foregoing, it will be understood 40 that my improved arch support may be readily applied to the foot and comfortably worn thereon without danger of displacement and that the support afforded by said device to 45 the transverse, longitudinal and metatarsal arches of the foot will tend to protect the wearer against and correct those impairments of the feet caused by falling arches.

Changes in the specific form of my invention, as herein disclosed, may be made within 50 the scope of what is claimed without departing from the spirit of my invention.

Having described my invention, what I claim as new and desire to protect by Letters 55 Patent is:

1. In a device of the class described, a yielding foot encircling band and an elongated arch bracing pad reaching forwardly of the band from the inside and at the bottom thereof, said band including a top instep engaging portion of non-elastic material and a bottom portion of elastic material, the instep engaging portion being cut low at the upper and lower edges thereof to bring said portion 60 well down on the foot and perforated to ven-

tilate the foot, said pad including flexible top and bottom pieces joined at their margins, and a resilient cushioning device encased between said pieces at the forward end of the pad and serving to arch said end transversely, 70 the shank of said pad being seamed at its side edges transversely of the elastic portion of the band and at its end, longitudinally of the band inside of the rear edge thereof, the application of the band to a foot requiring 75 the stretching of said band, the normal span of the band between the seams at the sides of said pad being less than the width of the shank of the pad, to effect the transverse arching of said shank through the elasticity 80 of said band.

2. In a device of the class described, a yielding foot encircling band including a top instep engaging portion of non-elastic material and a bottom elastic portion completing the 85 band, said top portion being cut low at its upper and lower edges to bring the same well down on the foot of the wearer.

3. In a device of the class described, an elastic foot encircling band and a flexible 90 pad arranged transversely of the band within the same, the bottom portion of the band lying under the pad, said pad being secured at its side edges to the band, the distance 95 along the band between the lines of attachment of said pad to said band being less than the width of the pad.

4. In a device of the class described, an elastic band adapted to be stretched over the foot and a flexible pad arranged transversely of the band within the same, the bottom portion of the band lying under the pad, said pad being seamed at the rear end thereof to and longitudinally of the band, the seamed 100 portion of said band being stretched in the sewing approximately to that extent to which said band is stretched when fitted on the foot.

5. In a device of the class described, an elastic band adapted to be stretched over the foot and a flexible pad arranged transversely 110 of the band within the same, the bottom portion of the band lying under the pad, said pad being seamed at the rear end thereof to and longitudinally of the band, the seamed portion of said band lying forward of the rear edge thereof and being stretched in the sewing approximately to that extent to which said band is stretched when fitted on the foot.

6. In a device of the class described, an elastic foot encircling band and a flexible pad 120 reaching forwardly of said band, the side edges of the shank of said pad being seamed to the inner side of the lower portion of said band transversely thereof, the distance along the band between said seams being less than the width of said shank, said pad including a cushion arranged at the forward end thereof and serving to yieldingly arch said end transversely and upwardly.

7. In a device of the class described, an 125

elastic foot encircling band and a pad, said pad including a flexible member secured to said band and reaching forwardly thereof, also a cushion device carried by the forward 5 end of said member, said device consisting of a body formed with an upper convex surface and yielding wings reaching outward from

the sides of said body, said wings together with said body serving to yieldingly arch said forward end of said member laterally. 10

In testimony whereof, I have signed by name to this specification.

JOSEPH A. SKOGLUND.
